UNITED STATES PATENT OFFICE.

CHARLES G. TREFETHEN, OF TAUNTON, MASSACHUSETTS.

DESIGN FOR A WATER-COIL.

51,846.

Specification for Design.

Patented Mar. 5, 1918.

Application filed August 25, 1917. Serial No. 188,228. Term of patent 7 years.

To all whom it may concern:

Be it known that I, CHARLES G. TREFETHEN, a citizen of the United States, and resident of Taunton, in the county of Bristol and State of Massachusetts, United States of America, have invented a new, original, and ornamental Design for a Water-Coil, of which the following is a

specification, reference being had to the accompanying drawing, forming part thereof.

The figure represents a face view of a water coil embodying my new design.

I claim:

The ornamental design for a water coil as herein shown.

CHARLES G. TREFETHEN.
